UNITED STATES PATENT OFFICE

RAYMOND A. TAYLOR, OF FREDERICK, MARYLAND

SUBMARINE ESCAPEMENT DEVICE

Application filed November 28, 1928. Serial No. 322,488.

This invention relates to submarines, the primary object of the invention being to provide an escapement device for submarines so that the inmates of a submerged submarine 5 may escape to the surface of the water should the submarine be caused to sink due to an accident or damaged machinery.

An object of the invention is to provide means for maintaining an equalization of 10 pressure above and below the door or closure used in closing the escapement chamber or tube, so that the door may be opened readily.

A still further object of the invention is to provide means which may be operated by the 15 occupant of the escapement chamber or tube to the end that the last person left in the submarine may escape by manually operated means controlled from a point within the escapement chamber.

20 Still another object of the invention is to provide means for operating the door of the escapement tube which may be controlled manually or by air pressure at the will of the operator.

25 With the foregoing and other objects in view which will appear as the description proceeds, the invention resides in the combination and arrangement of parts and in the details of construction hereinafter described

30 and claimed, it being understood that changes in the precise embodiment of the invention herein disclosed, may be made within the scope of what is claimed, without departing from the spirit of the invention.

35 Referring to the drawings:

Figure 1 is a side elevational view of a submarine illustrating escapement tubes constructed in accordance with the invention as positioned thereon.

40 Figure 2 is an enlarged fragmental sectional view through the submarine and escapement tube.

Figure 3 is an enlarged fragmental view 45 of the escapement tube, the door or closure of the tube being shown in its open position.

Referring to the drawings in detail, the reference character 5 indicates a submarine in which the escapement tubes forming the subject matter of the present invention, are installed.

Each escapement tube embodies a cylindrical body portion 6 which is of a diameter and height to permit a person to stand erect in the tube. At the upper end of the escapement tube is a depression formed with an irregular surface conforming to the contour of the edge of the door or closure 7 of the tube, so that a water tight connection between the closure 7 and upper end of the tube 6 will be assured. A threaded bolt 8 extends 55 through the upper portion of the tube 6 and passes into a threaded opening of the closure 7, as clearly shown by Figure 2 of the drawing, so that the closure will be held down under normal conditions.

The closure 7 is hingedly connected to the body of the submarine, by means of the hinges 9 and is provided with a connecting member 10 to which the link 11 is connected, the link 11 having pivotal connection with the arm 12, 65 which is formed integral with the arm 13 that rocks on the bracket member 14. An operating rod 15 extends through the upper wall of the submarine and connects with the arm 13, through the medium of the link 16, 70 there being provided a gasket 17 surrounding the opening through which the rod 15 operates, to insure a water tight connection at this point.

An operating lever indicated at 18 connects 75 with the rod 15 and has pivotal connection with the link 19 which in turn is pivotally connected with the block 20 which is secured to the inner surface of the submarine body portion.

80 Disposed directly above the operating lever 18 is a cylinder 21 in which the piston 22 operates, the piston including a tubular portion 23 in which the rod 24 operates, the rod 24 being pivotally connected to the operating 85 lever 18. The reference character 25 designates a compressed air tank which may be filled with air in any suitable and well known manner, and as shown communication is established between the tank 25 and cylinder 90 21, through the pipe 26. A valve 27 is disposed in the pipe line and may be operated to control the passage of compressed air to the cylinder 21 to operate the piston. Another valve 28 is disposed in the pipe line 95 100

and extends into the escapement tube so that this valve may be operated from a point within the escapement tube, to control the passage of air to the cylinder 21.

5 A water inlet pipe 29 has its upper end 30 extended through the deck of the submarine, the pipe extending downwardly where it passes into the escapement tube 6 at its lower end. A valve 31 is provided in the pipe 29 10 and may be operated to control the passage of sea water into the escapement tube. Another pipe 32 connects with the pipe 26 and has its lower end disposed adjacent to the bottom of the tube 6 to admit water at the 15 bottom of the tube 6, the pipe 32 being mounted within the tube 6. The reference character 33 indicates a valve which may be controlled by the person within the escapement tube so that water may enter through 20 the pipe 32. The reference character 34 designates an outlet pipe that has its upper end disposed at a point within a recess 35 formed in the closure 7, the lower end of the pipe extending through the wall of the tube 6 25 where it is supplied with a valve 36. This outlet pipe 34 permits air to pass from the escapement tube as the water enters the escapement tube through the pipe 32, and when the escapement tube becomes filled with water 30 the water will pass from the tube through the pipe 34 indicating to the occupants of the submarine that the escapement tube has been filled with water. The valve 36 is now closed while the valves 31 and 33 remain open so 35 that the pressure on opposite sides of the closure 7 is equalized to the end that the closure may be easily operated by the lever 18. When the closure 7 is moved to its open position, the person in the tube ascends to 40 the surface of the water. A valve 45 is also in the pipe line 34 and affords means for cutting off the passage of water through the pipe 34, from a point within the escapement tube. A pump indicated at 37 is in communication 45 with the interior of the escapement tube, through the pipe 38 so that water may be pumped from the escapement tube after a person has left the escapement tube, so that another person may enter the tube. Water 50 passes from the pump, through the pipe 39 that has its discharge end disposed exteriorly of the submarine, there being provided a check valve 40 so arranged that water cannot enter the pump through the pipe 39. The 55 escapement tube is provided with an entrance opening normally closed by means of the door 41 supported by the hinges 42, there being provided a pivoted latch 43 operated by either side of the door so that when a person enters the escapement tube he may lock the door.

In the use of the escapement tube, it is to be understood that the occupants of the submarine before entering the escapement tube 6, are supplied with water proof suits 60 embodying helmets so that sufficient breath-

ing space is provided to supply air until the persons reach the surface of the water. As a person enters the escapement tube 6, the door is closed and the valve 31 is opened allowing sea water to enter the escapement 70 tube at the bottom thereof until the escapement tube is filled.

When a person is to be released from the escapement tube, the valve 36 is closed and the valve 31 remains open. The bolt 8 is now 75 released and the operating lever 18 is pulled downwardly causing the closure 7 to swing upwardly to its open position as shown by Figure 3.

After the person has been released from 80 the escapement tube the operating lever 18 is moved to close the closure 7 and the water is pumped from the escapement tube whereupon another person to leave the submarine enters 85 the escapement tube and this operation is repeated.

The last person to leave the submarine now 90 operates the lever 18 to move the closure 7 to its closed position and after the water has been pumped from the escapement tube, the person 95 enters the escapement tube locking the door 41 after him. The valve 36 is of course left open and the valve 45 is operated to allow air to pass through pipe 34. Valve 33 is now operated allowing sea water to enter 95 the escapement tube and when the escapement tube becomes filled with water, valve 45 is closed.

When the person in the escapement tube 100 is ready to leave the tube, the person operates the valve 28 allowing air to pass from the tank 25 to a point above the piston 22 in cylinder 21. It is obvious that the piston will move downwardly moving the operating lever 18 to move the closure 7 to its open position 105 whereupon the person in the escapement tube will float to the surface of the water.

In order that the closure 7 may be moved to its closed position with the least possible 110 resistance, a one-way valve 44 is provided in the closure which valve allows water to pass through the opening in the closure as the closure moves downwardly.

I claim:

1. An escapement tube for submarines, including a body portion secured within the submarine, a closure for normally closing the body portion, an operating mechanism including a cylinder, a piston operating in the cylinder, said piston having a tubular extension, an operating lever, a rod connected with the operating lever and extending into the tubular extension to permit the operating lever to move independently of the piston, means for directing compressed air to the cylinder to operate the piston and operating lever, and means operated by the operating lever for moving the closure to its open and closed position.

2. An escapement tube for submarines, in-

cluding a body portion secured within a submarine, the upper end of the body portion being open, a closure for normally closing the open end of the body portion, mechanical means operated exteriorly of the body portion for moving the closure to its open position, pneumatically controlled means controlled from a point within the body portion for operating the mechanical closure operating means, and said mechanical closure operating means adapted to be operated independently of the pneumatically controlled means.

3. An escapement tube for submarines, including a body portion secured within a submarine, the upper end of the body portion being open, a closure for normally closing the open end of the body portion, mechanical closure operating means connected with the closure, pneumatically controlled closure operating means including a cylinder and a piston, means for connecting the piston to the mechanical closure operating means to operate the mechanical closure operating means, and said mechanical closure operating means adapted to operate independently of the pneumatically controlled closure operating means.

In testimony that I claim the foregoing as my own, I have hereto affixed my signature.

RAYMOND A. TAYLOR.
